NATURAL COLORS FLOATING SIGNAL

Raymond C. Hitt, Seattle, Wash.

Application March 17, 1943, Serial No. 479,529

1 Claim. (Cl. 9—8)

This invention relates to smoke and vapor signals, and particularly to such signals to be operated in daylight hours on the high seas, as in cases of ship-wrecked survivors. During war times, and other occasions when ships are wrecked, the survivors sometimes float for many days or weeks in small boats, without being discovered by searching planes. Black smoke signals are often overlooked by observers flying over them at high elevations, or at distances, because such colored signals are not readily discovered against the surface of the water which appears dark from above. It is therefore important that such signals may be provided of yellow or light colors which may be readily discovered against a dark background or sea, particularly from elevations above the sea. In some instances chlorate of potash has been used for signals by production of dark or black smoke, or other colors, but chlorate of potash has been found dangerous in use, particularly when carried in quantities together sufficient for a signal device as the same may explode or become ignited spontaneously or by heat in the tropics, and cause injuries to ships and boats and persons thereon. It is also important that receptacles be provided for transporting such materials or chemicals for such signal purposes, which shall be of relatively light material and yet strong to withstand hard usage and to require little space for storing in small boats, and be sufficiently buoyant when loaded to readily float on the surface of the ocean while giving out the desired signals.

Some chemicals suitable for producing desirable colors in smoke and gases generally leave or form a body of hot ashes or pumice through which the smoke when rising, becomes faded and loses its natural and desirable colors for observing at a distance.

It is therefore among the objects of this invention to provide a receptacle for retaining suitable smoke producing chemicals, for packing and transportation on small life boats and ships, with means for utilizing suitable chemicals for producing desirable light colors in smoke and vapors when burned, and to provide means for prevention of the fading of suitable colors before they are discharged from the receptacles for observation.

With these and other objects to be hereinafter stated, I have illustratively exemplified my invention by the accompanying drawing, of which: Figure 1 is a perspective view of the device complete and wrapped in a waterproof sheath for

transportation and use. Figure 2 is a vertical cross section of the device and interior parts. Figure 3 is a cross section view looking down from lines 3—3 on Fig. 2. Figure 4 is a perspective view of a non-combustible tube with perforations for discharging colored smoke and vapors to prevent the same from being faded by passing through burned material.

Like characters on the different figures represent like parts. The letter A represents tube or casing formed from fabric or other suitable material with sufficient strength for the purpose and yet lighter in weight than heavy metals, for buoyancy when cast overboard into the sea. One end 10 of the tube, which for convenience and descriptive purposes is designated the bottom, is partially filled with clay 2, or other suitable material to support a charge of smoke material or powder 3, and to protect the same from water, 15 and also to provide weight to cause such lower end to sink and sustain the device in perpendicular position when used for a signal on the water, such weight however being insufficient to cause the upper portion of the device to remain 20 immersed. The upper end of the tube is closed by a suitable plug 6 which may be of wood or other suitable material, and provided with relatively small hole 7 through the center thereof, for escape of smoke and vapors, but insufficient 25 to provide a large supply of air to cause blazing of the smoke producing material. A pair of fuses 4 and 5 are trained through the hole 7, and the lower ends 5' and 4' are rested against the charge of powder 3 for readily igniting the charge 30 when desired. The upper ends of the fuses shown as 5' are pressed down upon the top surface of the plug 6 and thereto affixed by a patch 9 of material for being ignited by friction and thereby igniting the fuses, such as the usual material used for match heads. The upper ends of 35 the fuses and patch are protected from undesired friction or injury during transportation or storage by a cap 12, which may be of any suitable material, and is provided on its upper surface with a patch 13 of friction material for causing the patch 9 to ignite, and may be so used by the operator manually by removing the cap and inverting the same and rubbing the patches together. A depression 8 on the underside of the cap provides further protection for the patch 40 9. A ribbon or tape 10 is preferably attached at one end to the cap, and carried thence over the cap and down one side of the tube, and terminates in an outturned tip 10' to be readily 45 grasped by the operator, when necessary to re- 50 55

move the cap. Normally the entire device is sheathed with a water proof covering 11 to prevent moisture or water injuring the powder during transportation. The tip 10' being at a distance from the top of the cap prevents water from seeping along the ribbon for such distance. The charge of powder is solidly compressed in the lower portion of the casing, and preferably composed of an oxidizing agent, free from chloride of potash, with an oxidizable substance, such metallic sulfides, or dyes for providing desired colors when the combustion occurs. For the purpose of providing an orange colored vapor, the following combination may be used: oxidizing agents such as inorganic nitrates as barium nitrates with organic ammonium and zinc picrates together with oxidizable substances such as amino-azo-benzine with beta-naphthol and wood flour. As such material when burning forms considerable heavy ashes or pumice which destroy and fade out the natural colors of the smoke or vapors if passed therethrough, it is necessary to provide means for the escape of such smoke and vapors laterally into and up through a central flue 14 projected centrally and perpendicularly through the material, such smoke and vapors to pass from beneath such pumice laterally as the combustion progresses downward. In order to prevent any of the material or powder from falling into the flue, a noncombustible tube 15 is provided, preferably from asbestos composition, for slidable adjustment into the flue, and holes or large perforations 16 through the walls of the tube permit the smoke and vapors from the burning powder to pass into the tube and out from the top thereof, into a central chamber B, above the powder and beneath the plug, and thence out through the hole 7. A thin paper wrapper 17 is first placed over the tube, to prevent any of the powder from prematurely or otherwise entering the same from top or bottom and through the perforations. This paper burns away as the combustion of the powder progresses, to permit free passageways for the smoke and vapors. The portion over the top of the tube is also burned and destroyed by the combustion.

The chamber or space B is of suitable size to

first contain sufficient air to provide buoyancy for the device, and cause the same to rise to the surface when cast overboard and sustain the top above the water, and as so positioned and formed centrally and over the powder the chamber dimensions of the device may be retained relatively small, for easy transportation. As the original air is first consumed by the first burning powder, the chamber is filled with heated vapor and smoke, which rapidly flows out through the hole 7 and prevents any entrance of water into the chamber even in case of immersion of the device beneath waves.

The relative small sizes required for the devices 15 permit the storage of a sufficient number thereof to meet emergencies of a life boat crew or castaways from wrecks, and as no tools are required for opening and igniting the device, a bright smoke or signal may be produced under all circumstances, and each device may be sufficient to provide such signals for relatively long periods.

Having described my invention I claim as new:

A floatable device for providing a smoke signal for daylight use at sea, comprising a tube, a relatively heavy base therein for maintaining the tube in perpendicular position while floating, a charge of smoke producing chemicals packed above the base, and provided with a perpendicular flue through the charge for flow of smoke therefrom as the charge is burned to prevent loss of the natural colors provided by the charge, a fuse for igniting the charge, the tube provided with an open space centrally located above the charge for buoyancy and for formation of smoke and gases therein above the charge, a cover for the upper end of the tube provided with a relatively small hole therein for passageway for said ignition fuse and for escape of smoke and vapors from the burning charge, a plaster of ignition material on the top of the cover adjacent the upper end of said fuse and a cap for protecting the plaster and provided with abrasive material thereon for igniting the end of the fuse, said fuse extended to the charge for igniting the same, and a waterproof sheathing over the device to prevent the entrance of moisture.
